UNITED STATES PATENT OFFICE.

GERALD M. HART, OF WILKES-BARRE, PENNSYLVANIA, AND LEWIS L. EVANS, OF BRIDGEPORT, CONNECTICUT.

CIRCUIT-CLOSER.

1,246,422.

Specification of Letters Patent. Patented Nov. 13, 1917.

Application filed September 11, 1916. Serial No. 119,491.

To all whom it may concern:

Be it known that we, GERALD MICHAEL HART, a citizen of the United States, residing at Wilkes-Barre, in the county of Luzerne, State of Pennsylvania, and LEWIS LLEWELLYN EVANS, a citizen of the United States, residing at Bridgeport, in the county of Fairfield and State of Connecticut, have invented certain new and useful Improvements in Circuit-Closers; and we do declare the following to be a full, clear, and exact description of the invention, such as will enable others skilled in the art to which it appertains to make and use the same.

15 This invention relates to improvements in electric switches or circuit closers.

The object of the invention is to provide a device of this character so constructed as to render it certain in its operation and insure 20 a perfect electrical connection between the fixed and movable contacts thereof.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:

Figure 1 is a side elevation of a switch constructed in accordance with this invention;

Fig. 2 is a plan view thereof;

Fig. 3 is a horizontal section taken on the line 3—3 of Fig. 1;

Fig. 4 is a transverse vertical section taken 40 on the line 4—4 of Fig. 1;

Fig. 5 is a detail horizontal section taken on the line 5—5 of Fig. 1;

Fig. 6 is a detail vertical section taken on the line 6—6 of Fig. 3;

45 Fig. 7 is a detail vertical section of a modified form of the invention.

In the embodiment illustrated, a supporting base 1 is shown constructed of brass or any suitable metal with a pair of laterally 50 extending laterally spaced terminal posts 2 and 3 mounted in insulated relation thereon, preferably near one end of said base plate.

These posts 2 and 3 are preferably secured to a plate 4 of insulation by means of screws 55 5, the heads of which are countersunk in

said plate 4 to prevent contact of said heads with the base 1. These posts 2 and 3 are thus rigidly secured to the plate 4, but in Fig. 7 they are indicated at 2^a and are shown pivotally mounted in U-shaped brackets 2'. 60 Springs 3' are secured to plate 4 and bear on the posts 2^a for a purpose to be described.

The plate 4 is fixed to the base plate 1 by screws or any other suitable means and serves to completely insulate the terminal 65 posts from said base plate. The free ends of the posts 2 and 3 are bifurcated and have peripherally grooved rollers 6 and 7 mounted therein. These terminals 2 and 3 are equipped with binding posts in the form of 70 headed screws 8 which are designed for connecting the terminals with the opposite poles of an electric source, wires 9 and 10 being shown for this purpose.

Two bearing arms or brackets 12 and 13 75 project laterally in parallel and spaced relation from the base plate 1 and between them is mounted a shaft 14. A sleeve 15 is rotatably mounted on the shaft 14 and has extending therefrom and preferably made 80 integral therewith two sector-shaped segmental plates 16 and 17. These plates are arranged in parallel and spaced relation with their peripheral edges in transverse alinement, and are connected and maintained in properly spaced relation by combined spacers and connectors 18 formed integral with the arcuate edges of said plates. Lugs 19 project beyond the outer faces of the plates for a purpose set forth later. 90

Arcuate strips 20 of insulating material are secured to the arcuate edges of the plates 16 and 17 being in the form of radial extensions on said plates and secured thereto by suitable fastening elements which pass 95 through laterally extending lugs 21 integrally formed on the opposite faces of the inner edges of said strips and through the spacers 18 and lugs 19. These insulating strips 20 have formed therein adjacent one 100 end alined notches 22 which coöperate to form a seat for a U-shaped contact 23, the legs of which form continuations of the ends of the strips and the free ends of said legs are arranged flush with the peripheral edges 105 of the strips. The ends of the legs of the contact 23 are straight-edged to provide cam faces for engagement with the rollers 6 and 7, said legs being shown increasing in length from their inner edges toward their 110

outer edges so that when the plates are moved inward toward the base plate, these cam faces will be forced into the grooves of the rollers and insure a perfect electrical connection between the contact 23 and the rollers. The edges of the strips 20 and the ends of the legs of the contact 23 are beveled on both faces to adapt them to enter the grooves of the rollers 6 and 7. The spacer 10 or connector 18' which connects the ends of the plates which carry the contact 23 is made integral with said plates and suitable fastening elements are passed through the intermediate portion or cross bar of the U-shaped contact 23 and through said spacer 18', thereby securing said contact in operative position, insulating plates 24 and 25 being arranged on opposite faces of said contact cross bar.

20 An arm 26 is secured to the sleeve 15 and is designed to be connected with any suitable actuating means not shown and which when operated serves to oscillate the connected plates 16 and 17 to bring the contact 23 into or out of engagement with the grooved rollers 6 and 7. When the contact engages said rollers an electric circuit is completed through the wires 9 and 10 which are connected with a battery not shown.

30 Owing to the cam formation of the free ends of the legs of the contact 23, rotation of the plates 16 and 17 in the direction of the arrow *a* will bring said contacts into engagement with the rollers 6 and 7 and will insure a perfect connection between said contact 23 and the terminal rollers even though wear should occur either on said contact or on the grooved faces of the rollers.

In the use of the modified form shown in 40 Fig. 7, the operation is the same as that above described the springs 3' serving to hold the rollers of the terminals 2* on which said springs bear in yielding engagement with the movable switch member.

45 We claim:

1. In an electric circuit closer, a pair of laterally spaced terminal posts having rollers mounted to rotate therein, pivotally mounted arcuate members with their peripheries positioned for engagement with the peripheries of said rollers, and straight-edged connected contacts carried by the peripheries of said arcuate members to form cam faces relative to said arcuate members for simultaneously engaging said rollers and insuring contact therewith.

2. In an electric circuit closer, a pair of laterally spaced terminal posts having rollers mounted to rotate therein, pivotally mounted arcuate members with their peripheries positioned for engagement with the peripheries of said rollers, and a U-shaped contact member spanning the space between said arcuate members with the legs thereof mounted in the peripheries of said members and increasing in length toward their outer edges to provide a cam engagement between said legs and rollers.

3. A circuit closer comprising a base plate, a pair of laterally spaced terminals projecting laterally therefrom, bearing brackets extending laterally from said base plate at points spaced from said terminals, laterally spaced connected segmental plates with their apices pivotally mounted in said brackets and their peripheries extending toward and engaging said terminals, contacts arranged in the peripheries of said segmental plates and connected for the passage of an electrical current through them, and means for operating said plates to engage and disengage said contacts and terminals.

4. A circuit closer comprising a base, a shaft supported thereby, a pair of connected segmental plates rotatably mounted on said shaft, a pair of roller terminal contacts positioned to frictionally engage the peripheries of said plates, and an insulated U-shaped contact with the legs thereof located in the peripheries of said plates with its cross bar spanning the space between them.

5. In an electric circuit closer, a base plate, a pair of insulated laterally spaced terminal posts mounted thereon, grooved rollers carried by said posts, laterally spaced 95 bearings on said plate, a pair of laterally spaced connected sector-shaped plates mounted to rotate in said bearings with their arcuate edges equipped with insulation and beveled to engage grooves in said rollers, 100 connected contacts arranged in said insulated plate edges, and means for operating said plates to bring said contacts into and out of engagement with said rollers.

In testimony whereof we have hereunto set our hands in the presence of two subscribing witnesses.
